UNITED STATES PATENT OFFICE

FRANK GRAHAM HOLMES, OF TRENTON, NEW JERSEY, ASSIGNOR TO LENOX, INC., OF TRENTON, NEW JERSEY, A CORPORATION OF NEW JERSEY

DESIGN FOR A PLATE OR SIMILAR ARTICLE

Application filed September 5, 1929. Serial No. 32,673. Term of patent 14 years.

To all whom it may concern:

Be it known that I, FRANK GRAHAM HOLMES, a citizen of the United States, and resident of Trenton, in the county of Mercer and State of New Jersey, have invented a new, original, and ornamental Design for a Plate or Similar Article, of which the following is a specification, reference being had to the accompanying drawing, forming part hereof, which drawing is a face view of a

plate or similar article illustrating my new design, it being understood that the ornamentation shown between the two dotted radial lines is continued or repeated throughout the border of the plate.

I claim:

The ornamental design for a plate or similar article, as shown and described.

FRANK GRAHAM HOLMES.
